[57] CLAIM

The ornamental design for a plant holder, substantially as shown and described.

DESCRIPTION

FIG. 1 is a front and top perspective view of a plant holder showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view taken from the right of FIG. 1, the left side being a mirror image.
